UNITED STATES PATENT OFFICE.

MARIO GOITRE, OF TURIN, ITALY.

TAB OF GUIDE CARDS FOR CARD INDEXES AND THE LIKE.

Application filed April 16, 1921, Serial No. 461,824. Renewed September 5, 1922. Serial No. 586,356.

To all whom it may concern:

Be it known that I, MARIO GOITRE, a subject of the King of Italy, residing at Turin, Italy, have invented certain new and useful

- 5 Improvements in Tabs of Guide Cards for Card Indexes and the like; and I do hereby declare the following to be a full, clear, and exact description of the invention, such as will enable others skilled in the art to which
 10 it appertains to make and use the same, reference being had to the accompanying drawings, and to letters or figures of reference marked thereon, which form a part of this specification.
 15 The present invention relates to improvements to the form and disposition of the tabs of guide cards for card index and the like.

In accordance with the present invention, 20 the tabs of the principal guide cards, corresponding with the first letter or initial sign of a word or symbol, have a constant determined given width, equal for instance to double the size of a modulus or unit of a
 25 pre-established measure, and are all placed on the same row parallel with the sides of the card index.

The tabs of the secondary guide cards corresponding with the successive letters and 30 signs destined to compose with the initial letter or sign, a given word or symbol, all initiate and start from the middle of the tab of the initial letter and they extend or are amplified by regular gradation towards
 35 the right, by an amount equal to two, three, four, etc., times the modulus of measure, according as the letter or sign which they indicate is the second, the third, the fourth, etc., letter or sign of the word or symbol destined to be composed with the initial one.

Besides this, every secondary tab carries, at intervals equal to the modulus of measure, and starting from the left edge which is placed in alinement with the middle of the 45 tab of the initial letter, clearly visible signs, made for instance by notches cut on the upper edge of the tab, which will be found equal in number on any given tab to the number representing the order of the tab, less one. The number of these notches 50 serves to indicate the position after the initial letter indicated by the above mentioned initial tab, of the letter on the secondary tab, in the word or symbol destined to be composed with the initial letter or sign.

Sometimes in order to file a number of

index cards in a given space in the card index, guide cards are inserted bearing tabs for one or more complete words or symbols. In such a case the tab of the relative guide 60 card, always proceeding from the middle of the tab of the initial letter, is extended to the point of reaching at least the extreme length of the secondary tabs, while to distinguish it from the latter its upper edge 65 does not bear any notches.

To give a clear idea of the present invention a form of execution of the object of the same is diagrammatically illustrated, by way of example only, on the annexed 70 drawing, in which: Fig. —1— shows the whole of the guide cards of a part of a card index with tabs in conformity with the present invention; Figure —2— shows the amplification of a portion of the preceding card 75 index.

As shown in Figure —1—, the tabs —1— of the principal guide cards bearing the initial letters A, B, C, D, E, F, G, of a word or symbol, have a constant width equal for 80 instance to twice the size of the modulus or unit of pre-established measure. These tabs are then all placed on the same row parallel with the sides of the card index, in the drawing they are seen adjacent to the left 85 side of the same.

Among the principal guide cards corresponding with the above mentioned initial letter, there are interspersed as usual, one or more secondary guide cards corresponding 90 with the first letter of the nominative after the initial one, and so on, while between the whole of the several guide cards the cards —11— may be conveniently inserted.

To fix one's ideas the better, it is as well 95 to consider the secondary guide cards inserted between the principal ones, corresponding with the initial C and D. Before all it must be observed that the tabs of the secondary guide cards have all their initial starting point from the middle of the tabs —1— of the principal guide cards and extend in a graduated scale towards the right to an extent equal to two, three, four, etc. times the modulus of measure, according as 100 they correspond with the first, second, third, etc. letter of the nominative after the initial one. In fact the secondary tabs —2— corresponding to the first letter of the nominative after the initial letters such as those marked A, E, O, R, after the initial letter C 105 have an extent equal to twice the modulus.

Those marked —3— corresponding with the second letter of the nominative after the initial one, M, S, V, R, M, I, have an extent equal to three times the modulus. Those 5 marked —4— corresponding with the third letter of the nominative after the initial letter, C, have an extent equal to four times the modulus. These marked —5— corresponding with the fourth letter of the nominative 10 after the initial letter, O, have an extent equal to five times the modulus. And so on. These secondary tabs clearly show one, two, three, etc., signs formed for instance with notches —12—, cut on the upper 15 edge of the tab at equal distances to a modulus, starting from the left edge, according as they correspond to the first, second, third, etc., letter of the word after the initial. These notches serve at the same time to indicate 20 at once the position occupied by the letter signed on the tab, in the nominative composed of the preceding initial letter.

Owing to this arrangement it become easy even in a complicated card index, looking 25 from left to right to the top, and mentally forming the word with the letters signed on the several tabs, keeping in mind the position of such letters indicated by the notches marked on the tabs, immediately to fix the 30 point where the index card —11—, corresponding with a given nominative must be inserted or found. Thus with the nominative “Campiglia” the position between —Camp— and —Campo— is found immediately; for the nominative “Campobasso” the 35 position between —Campo— and —Cas—, is found immediately. And so forth.

This new type of tabs of guide cards also allows, without any change being required 40 in the existing guide cards, unlimited amplification of detail in a given index, which is not possible with usual guide cards, where the tabs of the different guide cards, have in fact a zig-zag arrangement for which reason 45 any amplification whatever requires the displacement of the tabs, involving the substitution for the existing guide cards of others, having the tab in a suitable position. Such a possibility of amplification is shown 50 as an example in Figure —2—, which illustrates an amplification of the space —13— of the card index in Figure —1—, which space comprehends the letter F, as an initial and the letter I, as the first letter after the 55 initial one. From this Figure —2— the result is seen that all the guide cards with their relative tabs shown in Figure —1— have been preserved, besides between the several guide cards, several amplification 60 have been made. The first amplification effected was between FA, and FE. In this first amplification the case is contemplated that a number of nominatives have been presented such as “Farmacia,” for which it 65 would be useful to insert a guide card bear-

ing a tab —6— with such a nominative in full. This tab starting as usual from the middle of the tab of the initial F, is extended sideways to the right for an extension not less than the greatest width of the 70 secondary tabs; to distinguish it from the latter, such a tab does not show or bear on the upper edge any notch or sign whatever.

When the different nominatives in “Farmacia” have to be divided by a successive 75 nominative, as for instance the proprietor’s name, in correspondence with this nominative may be initiated an alphabetical and secondary classification by suitable guide cards; whose principal tabs of the initial letters —7—, always having the width of 80 two times the modulus are placed according to a row parallel with the sides of the card index, but displaced with regard to the row according to which the principal tabs of 85 the initial letter —1—, are placed with regard to the primary classification.

In the amplification between Fer, and Feri, the example has been shown of a number of nominatives “Ferrero,” corresponding 90 to which is disposed a guide card with tab —8—, bearing in full the above mentioned nominative. Even here if an ulterior subdivision according to the Christian name is necessary, a secondary classification may 95 be initiated by means of suitable guide cards bearing tabs for initial letters —9—, with the relative secondary tabs —10— extending gradually to the right, and with interposed guide cards having tabs with the name in 100 full, as “Antonio” —14—, “Giuseppe” —15— etc. If an ulterior subdivision is required, for instance, for towns, is possible to initiate, always more towards the right on the card index, a third classification having 105 guide cards with initial tabs —16—, always two times the modulus in width, placed on the same row parallel with the sides of the card index, but displaced towards the right with regard to the corresponding initial tabs 110 of the first and secondary classification. Even in the third classification, subdivisions may be effected by means of secondary tabs —17—, —18—, for the first, second, etc. letters after the initial one, and also guide 115 cards may be inserted with tabs for nominatives in full —19—, as “Torino.”

From the foregoing it is seen how the amplification of the original card index may be effected either by simply amplifying the primary classification, or by inserting secondary and tertiary classifications, but applied according the same methods, without any change being made in the primary classification.

It is evident that the above described examples are given solely to explain and not to limit definitely, and that therefore the present invention is in no way limited to the precise arrangements described and illustrated,

but that without departing from the principles above explained the invention may comprise any variation required or considered necessary or advantageous in practice.

5 I claim:

1. An improved arrangement and conformation of the tabs of the guide cards for card index and the like, comprising tabs corresponding with the first letter or initial 10 sign of a word or symbol and having a determinate and unchanging width, equal to twice the size of a modulus or unit of a pre-established measure, and all arranged on the same row parallel to the sides of the card 15 index;—the tabs of the secondary guide cards, corresponding with the successive letters or signs, destined to compose with the initial letter or sign a given word or symbol, all having their initiative departure from 20 the middle of the tab of the initial letter and extending gradually towards the right to an extent equal to two, three, four, etc., times the modulus, according as the letter or sign that they indicate is the second, the third, 25 the fourth, etc. letter or sign of the word or symbol destined to be composed with the initial letter;—the secondary tabs each bearing at intervals equal to the modulus and starting from the left edge placed according to 30 the middle of the tab of the initial letter, clearly visible signs on the upper edge of the tab, which indicate multiples of the modulus and serve to indicate the position, after the initial, of the letter borne by each tab;—the 35 tabs of words or complete symbols always starting from the middle of the principal tabs of initial letters and extending side-

ways to the right to reach at least the length of the secondary tabs.

2. An improved multiple arrangement 40 and conformation of the tabs of the guide cards for card index and the like, as claimed in claim 1,—, comprising several series of guides with principal and secondary or full word tabs, disposed in successively displaced 45 positions sideways to the right in the same card index, and forming together the principal classification, secondary and tertiary classifications, etc., forming an amplification of the principal classification. 50

3. A card index comprising a plurality of 55 primary guide cards having tabs of a width equal to twice the size of a modulus of a pre-established measure arranged in a row parallel to the side of the card index, and secondary guide cards having tabs starting from the middle of the tabs of the primary guide cards and extending towards the right in multiples of the modulus. 60

4. A card index comprising a plurality of 65 primary guide cards having tabs of a width equal to twice the size of a modulus of a pre-established measure arranged in a row parallel to the side of the card index, and secondary guide cards having tabs starting from the middle of the tabs of the primary guide cards and extending towards the right in multiples of the modulus said secondary 70 tabs bearing visible signs at intervals equal to the modulus.

In testimony that I claim the foregoing as my invention, I have signed my name.

MARIO GOITRE.
